METHOD AND APPARATUS FOR TEMPERING
GLASSJean R. A. Prachay, Paris, France, assignor to
The American Securit Company, Wilmington,
Del., a corporation of DelawareApplication February 10, 1947, Serial No. 727,709
In France June 15, 1945Section 1, Public Law 690, August 8, 1946
Patent expires June 15, 1965

9 Claims. (Cl. 49—45)

1

In spite of the great amount of investigation that has taken place in the last fifteen years the problem of satisfactorily tempering by air blasts sheets of glass having a thickness of $\frac{1}{8}$ of an inch or less has not been satisfactorily solved. The conventional methods of projecting the blast from holes of relatively large diameter and in the walls of a blast box close to the sheet have not produced the desired sudden reduction of temperature and the use of high pressure blasts in such an arrangement has resulted in distortion of the hot and plastic sheet.

I have discovered that thin plates may be successfully tempered by employing air at a somewhat higher pressure than the practice heretofore employed and issuing it from long nozzles of relatively small diameter terminating relatively close to the sheet and close to each other, while leaving ample area for the escape of heated air from the surface of the plate between such surface and the face of the blast box from which the nozzles project.

Furthermore, as such an arrangement demands that the nozzles terminate close to the plate and that the initial chilling of the plate takes place with the nozzles in this position, my invention contemplates means for separating the two blast boxes during the insertion of the plate between them with means for insuring that the initial blasts shall be delivered only when the boxes are restored to their operative position relative to the plate.

Referring to the drawings in which corresponding parts are designated by corresponding marks of reference,

Figure 1 is a diagrammatic view in section illustrating this invention.

Figure 2 is a fragmental front elevation of the inner face of a blast box shown in Figure 3.

Figure 3 is a central vertical section of a device embodying my invention, and Figure 4 is a rear elevation thereof.

Figure 5 is a vertical section and Figure 6 is a front view of a modified form of my invention.

As diagrammatically shown in Figure 1, my invention embodies a blast box 2 on each side of the sheet to be tempered, each box having an air supply pipe 3 leading thereto and having projecting from its inner wall at numerous points elongated blast nozzles 4. As shown in Figure 2, these nozzles, while spaced from each other, are relatively close together. An arrangement which has been successfully employed embodies nozzles having an internal diameter of less than $\frac{1}{16}$ of an inch and terminating less than 1.2" from the surface of the sheet and having a length of over

2

2" and arranged less than 1.2" center to center, and fed with air at about the pressure of 7.1 lbs. per square inch. With this arrangement the nozzles occupy less than 4% of the space between the sheet and the box, thus leaving ample escape space for the heated air. The nozzles may be slightly truncated, as shown.

As it is important that the sheet be only subjected to the blast when the nozzles are close thereto and as it is inconvenient to insert a sheet between the opposite groups of nozzles when at proper blowing position, I provide means for moving the nozzles away from their blowing position and for supplying blast air to the nozzles when, and only when, they are at the proper distance from the sheet. For this purpose the plate from which the nozzles project is mounted to be shoved towards the sheet by the act of admitting air to the nozzles.

20 In Figures 3 and 4 this is accomplished by making the blast box with accordion sides, the outer plate 6 of the box being mounted in a frame 6a; while the inner plate 4a, carrying the nozzles, is carried on the inner ends of rods 8 working 25 through packing boxes 9b in the rear plate 4a and having on their rear ends helical springs between the outer surface of the packing box and the tension adjusting nuts 10a. An air supply pipe 13 is connected with the rear plate 6 of the air box.

20 In Figures 5 and 6 a construction is shown in which instead of merely moving the inner plate 4a of the box to and from the plate, the box is moved as a whole, it being mounted on the rods 8 guided in the packing boxes 10 as before. The rear plate 35 of the box is connected by the piston 16a with a piston head 16 working in an air cylinder 15. A suitable pipe 18 is provided for supplying air under pressure to the cylinder 15 from the distributing box 17 and from the same distributing box a plurality of pipes is provided letting air into the blast box, the cross sectional area of the pipe 17 being such that the piston head 16 will be shifted to the limit of its movement prior to the building up of pressure in the blast box. 40 In these constructions; namely, Figures 3, 4, 5 and 6, it will be seen that the admission of air to the blast box is accompanied by a simultaneous or prior motion of the nozzles towards the sheet to be tempered, thus accomplishing the purpose above set forth.

Having thus described my invention what I claim as new and useful and desire to secure by United States Letters Patent, is:

55 1. In a device for tempering thin glass sheets, the combination of a plurality of blast nozzles, a

movable support for said nozzles, pressure means for moving said support, an air conduit and means connecting said air conduit to said pressure means and to said nozzles, whereby upon the admission of air under pressure to said conduit the support is moved toward the glass sheet and air ejected from said nozzles.

2. In a device for tempering glass sheets, the combination of two movable boxes, one located on each side of the sheet to be tempered, each box being provided with a plurality of nozzles in communication with the interior of said boxes, supports for said movable boxes and a conduit for supplying cooling blast air to said boxes to move them toward the sheet interposed between them and to emit said blast air from said boxes through said nozzles.

3. In a device for tempering glass sheets, the combination of a nozzle plate located on each side of the sheet to be tempered, an accordion mounting for each of said plates forming the sides of a blast box therefor, means for supplying cooling air under pressure to the said boxes to shift the plates toward the sheet and means for carrying back the nozzle plates to their remote position when the cooling supply is cut off.

4. In a device for tempering thin sheets of glass, air chests located on each side of said sheet, said chests each closed on the side adjacent to the sheet by a movable nozzle carrying plate, means for admitting air to the interior of each of said chests for moving the nozzle carrying plate toward the sheet and means for retracting the nozzle plate upon the failure of pressure in the chest.

5. In a device for tempering thin glass sheets, the combination with a movable air box on each side of such sheet, nozzles mounted in the front plate of said box, a pneumatic drive cylinder for shifting the said box and means for simultaneously admitting air to the drive cylinder and to the box.

6. The hereinbefore described method of applying air blasts to a thin sheet which comprises moving blast nozzles toward the sheet under air pressure and creating the blasts from the nozzles

simultaneously therewith and by air pressure from the same source.

7. The hereinbefore method of applying an air blast to a thin sheet which comprises projecting air under pressure through a plurality of spaced nozzles on the sheet and simultaneously utilizing the pressure of the air feeding such nozzles to move the nozzles toward the sheet.

8. In a device for tempering glass sheets, an air chamber comprising a wall at least a portion of which is movable and a plate, said wall and plate movable toward and away from the plane occupied by the sheet when undergoing treatment, means for supporting said plate and wall for said movements, a plurality of nozzles provided with exit ends carried by the plate and opening into the chamber, means for moving said wall, plate and nozzles in a direction away from the plane of the sheet, a source of air under pressure, conduits between said source and said chamber to supply air simultaneously to the nozzles and to move the plate carrying said nozzles toward the glass sheet.

9. The method of applying chilling blasts of air to heated sheets of glass to temper the same which consists in admitting air under pressure to a plurality of blast nozzles movably arranged on opposite sides of the glass sheet and employing the pressure of said air to move the nozzles toward the sheet to apply the chilling blasts thereto.
